UNITED STATES PATENT OFFICE.

ROSS BURKHOLDER, OF MARSHALL, ILLINOIS.

ADJUSTABLE CONCRETE-CULVERT FORM.

1,219,434.

Specification of Letters Patent. Patented Mar. 20, 1917.

Application filed May 26, 1914. Serial No. 841,067.

To all whom it may concern:

Be it known that I, Ross BURKHOLDER, a citizen of the United States, and a resident of Marshall, in the county of Clark and 5 State of Illinois, have invented certain new and useful Improvements in Adjustable Concrete-Culvert Forms, of which the following is a specification, reference being had to the accompanying drawings, forming 10 a part of this specification.

This invention has for its object to improve the construction of that class of forms employed in constructing culverts to the end that a form may be provided which can be 15 adjusted to various widths and be readily removable after the concrete has firmly set. Further the invention has for an object to provide a concrete form which can be shipped in a knock-down condition, and be 20 readily reassembled.

With these and other objects in view, the present invention consists in the combination and arrangement of parts as will be hereinafter more fully described and finally 25 pointed out in the appended claim, it being further understood that changes in the specific structure shown and described may be made within the scope of the claim without departing from the spirit of the invention.

30 In the accompanying drawings forming a part of this specification, and in which like numerals of reference indicate similar parts in the several views:

Figure 1 shows a transverse sectional view 35 of a concrete form embodying my invention, disclosing the sheathing in position and the concrete cast about the same.

Fig. 2 is a section on line 2—2, of Fig. 1.

Fig. 3 is a perspective view of one of the 40 channeled side members.

Fig. 4 is a top view of a frame.

Fig. 5 is a bottom view of one of the frames.

Fig. 6 shows a set of frames as arranged 45 in building a culvert.

In carrying out the aim of my invention, I employ a plurality of knock-down frames which can be readily assembled and set upon suitable base boards, which after being 50 properly arranged are cased over.

In the drawings, A represents a suitable base upon which the culvert is to be cast. In forming the culvert I employ two base boards 10, 10, which are arranged in parallel 55 spaced relation, and are of a length equal to the length the culvert is to be made.

Set upon these base boards 10, are a plurality of frames, each of which includes two channeled side members connected by means of upper and lower spacing bars. 60

As shown in the drawings, each side member includes an outer bar 11, shown in Fig. 3, and two cleats 12 secured to the outer member in parallel spaced relation. The cleats are preferably wider at their lower 65 ends than at their upper ends, as is more clearly shown in Fig. 1. As disclosed, the upper ends c, of the outer bars 11 and cleats 12 are curved. These channeled side members are employed in sets of two, each cleat 70 having an upper bolt opening a, and a lower bolt opening b, arranged to receive the pivot-forming bolts 13 and 14.

Pivottally held to the upper bolts 14 are 75 the upper spacing bars 9, 9. These bars being adjustably secured by means of the bolts x.

In the drawings three such bolts x, are shown as holding the spacing bars together.

Pivottally held upon the lower bolts 13 are 80 the lower spacing bars 15, 15, which are also secured by means of suitable bolts x, this construction being clearly shown in Fig. 1.

As disclosed, the bolts 14 are located a certain distance below the upper curved ends 85 c, of the cleats 12, so that a socket is formed above these upper spacing bars 9 within which rest the ends of the arch members 18, 18. The arch bars 18 have their upper edges 90 19 curved, so as to form in conjunction with the curved ends c, a continuous arch upon which the top sheathing or casing 21 is placed, as clearly shown in Fig. 1.

In Fig. 1 a frame is shown arranged in its shortest adjustment. In widening the frame, 95 one of the bolts x, and one of the bolts 20 would be discarded, the arms being then secured by two bolts which would be located within the two outer openings within the arms. The arch members 18 would then also 100 only be held together by means of two bolts. In their extended condition, the arches rise, so that at each adjustment, the arch members are a predetermined distance farther away from the upper spacing arms 9. This is 105 necessary as the arch must be raised as the side walls are widened.

As shown in Fig. 6, the frames are used in sets any suitable number being employed.

From the foregoing it will be seen that I 110 provide a frame of simple construction which can be adjusted to various widths.

The frame is further, simple and inexpensive in construction, and both durable and efficient in operation, and the frames after the cement has set can be removed with ease, 5 accuracy and despatch.

Having thus described my invention what I claim as new and desire to secure by U. S. Letters Patent is:

A concrete culvert form comprising two 10 side members each including an outer member, two cleats secured to each outer member in parallel spaced relation, the upper ends of said cleats being curved, each cleat being provided with an upper bolt opening 15 and a lower bolt opening, upper pivot bolts within said upper openings, two upper spacing bars pivotally held upon the bolts within said upper openings, means to adjustably

secure said upper spacing bars, two bolts within said lower openings, two lower spacing bars pivotally held upon said lower bolts, means to adjustably secure said lower spacing bars, said upper pivot bolts being located a suitable distance below the upper ends of said cleats whereby a socket is 25 formed above said upper spacing bars, and two arch members having their upper edges curved and their ends held within said socket and against said outer bars, as, and in the manner shown.

In testimony whereof I affix my signature, in the presence of two witnesses.

ROSS BURKHOLDER.
